(57) **CLAIM**

The ornamental design for a combination cornhole and beer pong game set, as shown and described.

DESCRIPTION

FIG. 1 is an exploded top perspective view of a combination cornhole and beer pong game set, according to the present invention.

FIG. 2 is an alternative exploded top perspective view thereof.

FIG. 3 is a top perspective view thereof.

FIG. 4 is a bottom perspective view thereof.

FIG. 5 is a top perspective view of the invention as it appears while being transported.

FIG. 6 is a bottom perspective view of the invention as it appears while being transported.

FIG. 7 is a front view thereof.

FIG. 8 is a back view thereof.

FIG. 9 is a right view thereof.

FIG. 10 is a left view thereof.

FIG. 11 is a top view thereof; and,

FIG. 12 is a bottom view thereof.

1 Claim, 10 Drawing Sheets
